UNITED STATES PATENT OFFICE.

VIGGO STEPHAN KELLNER PETERSEN, OF GENTOFTE, DENMARK.

MILK-COOLING APPARATUS.

1,273,404.

Specification of Letters Patent. Patented July 23, 1918.

Application filed December 29, 1914. Serial No. 879,586.

To all whom it may concern:

Be it known that I, VIGGO STEPHAN KELLNER PETERSEN, of No. 3 Sponecksvej, Gentofte, in the Kingdom of Denmark, engineer, have invented certain new and useful Improvements in Milk-Cooling Apparatus; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 This invention refers to that kind of cooling devices which are used at the place of milking for cooling the new-milk. In the hitherto proposed devices of this kind, the cooling is accomplished by means of constant supply of fresh water (from a water-pipe or from a tank in the cooling apparatus itself), which after having sprayed the milk-tank is led off as waste water. According to this method of cooling, a large 20 quantity of water, many times greater than the quantity of cooled milk, is wasted, especially in the hot weather, when water is scarce.

In order to remedy this disadvantage, and 30 in consideration of the fact that the cooling-water pumped up into the tank disposed at the place of milking, for instance, above the cow-stable, should preferably be given a certain temperature previous to being used 35 as cooling-water, the cooling-device here referred to is, according to this invention, disposed in a closed circulating-pipe for the cooling agent, so that the cooling-water, after use, continuously returns to the tank. 40 Instead of ordinary water, ice-water, cold brine, etc., may be used.

In the accompanying drawings Figure 1 is a diagram of one form of construction of this apparatus, complete, Fig. 2 is the cooling-surface shown in Fig. 1, only on a larger scale, and partially in section, while Fig. 3 is another form of the cooling-surface, together with a filter.

The cooler-casing 8 (Fig. 1) which encloses the cooling-surface 3 is at the bottom connected with the cooling-water tank 9 by means of an adjustable pipe 10 and at the top by means of a return-pipe 11 which projects through an annular flange 55 12 on the cooler casing.

The new-milk is poured from the milk-

pail 14 into a distributing reservoir 13, seated on the flange 12 and the coarse dirt is retained by a wire strainer 15 (indicated by dotted lines) from which the milk is distributed around the top of the cooling-surface 3, down which it slowly flows in an evenly distributed thin sheet, its temperature all the time being gradually reduced, and at the same time the cooling-water in 60 the cooler-casing 8, owing to the warmth derived from the cooling of the warm milk, circulates of its own accord, in the direction from the bottom of the cooler up through the cooler-casing 8 and the pipe 11 65 to the top of the cooling-water tank 9. The cooled milk is filtered through the bacteriological filter 7, from whose bottom it runs out through a spout 5 down into the milk-tank 19. The neck of the milk-tank may 70 be covered by means of a lid 16, which may be in one piece with the spout 5, and which may carry a float 17, which will show when the milk-tank is full enough. The cooling-apparatus (3 and 8) and the distributing- 75 reservoir 13, 12, which may be loosely placed on or firmly attached to the cooling-apparatus, and the cooling-water tank 9, may be supported by a suitable stand 18.

Fig. 2 shows a suitable construction for 80 the filter. At the lower end of the cooling-surface 3 there is disposed, between a shoulder 4 and the spout 5, a double wire-cloth strainer 6, containing a cotton-wool filter 7. The spout 5 can, by means of a screw-threaded joint, bayonet-lock, or the like, be attached to a central opening in the cooler-casing 8.

In the form of construction shown in Fig. 3, the cooler-casing and cooling-surface are 90 united in a conical erect shell 38 suitably corrugated or stair-shaped, which envelops the cooling-chamber, and down whose outer surface the milk flows while the bacteriological filter 7 is disposed in a special box, 95 or container, 20, which has a detachable bottom formed with the spout 5 and can be covered with a lid 21.

From the distributing reservoir 13, with its wire strainer 15 and openings 22 in a 105 funnel-shaped plate 23, the milk is distributed around the top of the cone, and by gently flowing down the more and more widening cooling-surface, the milk is thus spread out into a thinner and thinner sheet, and is 110 in this manner quicker cooled, and the cooling-agent is better utilized, while the final

temperature is lower than in the construction with inverted cone shown in Figs. 1 and 2 with decreasing cooling-surface. From the foot of the cone, the cooled milk runs out into the filter 7 through a spout 24 or the like.

The cooling-chamber in the hollow cone 38 is, as shown by dotted lines, connected with the circulating-pipes 10, 11.

10 I claim:

1. In a milk cooling apparatus, the combination of a cooling receptacle, a horizontally corrugated wall therein forming a milk cooling chamber and a compartment 15 for the reception of a cooling liquid, a separate tank arranged above said compartment, a pipe connected to the top of the tank and detachably connected with the top of the compartment, and a pipe connecting 20 the bottom of the compartment with the bottom of the tank whereby milk flowing downward over the wall will automatically cause the cooling liquid to circulate in a counter direction through said compartment and 25 tank by reason of the difference of gravity of the liquid due to the difference of the temperature of said liquid.

2. A milk cooling apparatus, comprising a casing, a horizontally corrugated wall 30 mounted therein forming separate conduits through the casing, a separate cooling liquid tank mounted above the casing, a pipe connecting the top of the casing with the top of the tank, and a pipe connecting the bottom 35 of the casing with the bottom of the tank, whereby milk flowing downward over

the wall will cause the cooling liquid to circulate automatically in a counter direction through the tank and casing by reason of the difference of gravity of the liquid 40 due to the difference of temperature of said liquid.

3. A milk cooling apparatus, comprising a casing, a horizontally corrugated wall mounted therein and forming a central conduit 45 through the casing for the milk and an annular cooling compartment surrounding the conduit, a flange on the top of the casing covering the annular compartment, a distributing reservoir seated on the flange, 50 a separate cooling liquid tank mounted above the casing, a cooling liquid supply pipe connecting the bottom of the tank with the bottom of the annular compartment, and a return pipe for the cooling liquid projecting 55 through the annular flange and connecting the top of the casing with the top of the tank whereby milk flowing downward over the wall will cause the cooling liquid to automatically circulate in a counter direction 60 through said compartment and tank by reason of the difference of gravity of the liquid due to the difference of the temperature of said liquid.

In testimony that I claim the foregoing 65 as my invention, I have signed my name in presence of two subscribing witnesses.

VIGGO STEPHAN KELLNER PETERSEN,

Witnesses:

P. HOFMAN-SARY,
ERNEST BOUTARD.
